INVENTOR

Fig. 8. BY *William F. Schoenhard,*
H. M. Waisted,
ATTORNEY.

UNITED STATES PATENT OFFICE

WILLIAM F. SCHOENHARD, OF ST. LOUIS, MISSOURI

UMBRELLA

Application filed August 15, 1928, Serial No. 299,741. Renewed March 4, 1930.

This invention relates to certain new and useful improvements in umbrellas, the peculiarities of which will be hereinafter fully described and claimed.

5 The main objects of my invention are to provide an umbrella that can be folded up so as to go in a satchel, shopping bag, or pocket; secondly, to avoid the usual braces for the ribs; thirdly, to afford more head 10 room in the center of the umbrella; and fourthly, to provide certain novel features of construction hereinafter described and claimed.

In the accompanying drawing in which 15 like reference numerals indicate corresponding parts,

Fig. 1 represents a reversed plan of an umbrella embodying my improvements;

Fig. 2, a vertical sectional elevation on the 20 line 2—2 of Fig. 1, with the handle partly in section;

Fig. 3, a detail sectional view of one rib in stiffened condition;

Fig. 4, a similar view in flexible condition;

Fig. 5, a reversed plan detail of the holder for ribs and handle, with folded positions indicated;

Fig. 6, a vertical section of the holder on the line 6—6 of Fig. 5, showing the ribs in 30 position to be folded and the covering indicated by dash lines;

Fig. 7, an end view of the holder and ribs in folded position; and

Fig. 8, a side view of the same. 35 The numeral 1 designates the usual or any approved covering for the frame of ribs and handle mounted in a holder 3.

This holder is oblong, of cast metal preferably, having a depending steel rod 4 with a straight portion and its ends bent upward and riveted or otherwise secured near the ends of the holder.

On this rod are pivoted multiple rib sections,—7, 8, 9, 10, 11 and 12,—six being shown in this construction. These rib sections have their pivoted ends in one vertical plane—instead of in a horizontal plane around the handle as usual. The two end rib sections—7 and 10—are preferably loosely pivoted so as to slide up on the bent-up ends of said rod

4, and be held laterally in concave forks 13 and 14 respectively at the ends of the holder when in raised position, but are adapted to slide down to the straight portion of said rod and hang parallel to the other ribs in lowered position (Fig. 6). A flange 15 extends outward and slightly downward on the sides and fork ends of the holder, adapted to bear downward on all the ribs in raised position. 55

A handle 16 is slidably mounted in a hole 60 in a boss 17 near one end and offset from the central plane of the depending rod, and a spring catch 18 engages the boss when the holder is slid downward on the handle (Fig. 2), thus engaging the flange with the top of 65 the ribs and tensioning the covering. This movement is the reverse of the usual umbrella frame, as my holder with the pivoted ends of the ribs is slid downward to tighten the covering, and upward to loosen it. 70

My ribs are made in two or more sections, preferably tubular and connected by coil springs 19 or other flexible connections, preferably of the same outer diameter as the tubes so as to be flush with the outer sections 75 20, as shown.

To stiffen the ribs, a filler 21 is slidably mounted in each upper section of the ribs and is slid outward through said flexible connection part way into the outer section, by a cord 22 having a hook 23 to engage the outer end of the rib, and a terminal stop,—ball or other shaped-member 24 to pull the cord and filler to locking position against the tension of a spring 25 that connects the inner end of 80 said filler to the pivot end of the rib. (Fig. 3.) The retraction of said spring pulls the filler inward to unlocking position and the terminal stop-ball against the outer end of the rib, when the hook is disengaged 85 (Fig. 4).

The pivot ends of ribs 7 and 10 have holes 90 curved and enlarged to slidably pivot on the bent-up ends of the holder rod, the other ribs are also loosely pivoted as shown in Figs. 3 and 4, to allow them to assume the positions shown in Figs. 1 and 6.

The handle is also in multiple tubular sections, flexibly connected, and the joints adapted to be stiffened by filler pieces connected 100

5 by cord or wire, and the inner one controlled by a spring and the outer one provided with a cord and terminal stop-ball, similar to the ribs (Fig. 2). These terminal stops also form ornaments dangling from the drawn-out cords (Fig. 2), and close the outer end of ribs and handle (Figs. 4 and 6).

10 Fig. 6 shows the ribs in parallel flexible position hanging from the holder rod. These sections can then be folded over in planes parallel to each other (Fig. 7, shown reversed to facilitate such folding), with the outer sections hanging at the side of the holder as indicated in Fig. 5. The sections of the 15 handle are conveniently folded in one plane parallel to the holder and along the other side as indicated in Fig. 5 and shown in Figs. 7 and 8.

20 The covering remains attached to the top of the handle and is wrapped around the folded sections, making a small compact package adapted to be slipped into any convenient bag or other receptacle. As shown, the ribs are proportionately larger than 25 made, in order to show the construction clearly.

26 The covering has hooks 26 or other means for securing it to the outer ends of the ribs. As my holder is slid outward on the handle 30 to release the tension, the amount of the slack or fullness of the covering depends on this sliding distance, which may be greater according to the conical slant of the covering. When the conical slant is as shown in Fig. 2, 35 the hooks 26 may be disengaged from the ribs for folding,—or be provided with elastic connections 27 to the covering (Fig. 6), if the conical slant requires additional slack in the covering at the points of attachment to the outer ends of the ribs. It is desirable that 40 the covering be always connected—either permanently fastened or flexibly secured,—to the ribs, to facilitate opening and folding my umbrella.

45 I claim:

1. An umbrella comprising a handle, ribs, a holder and a covering,—said ribs being pivotally mounted in said holder, and said holder being slidably mounted on the handle 50 and having a flange above and adapted to bear downward on all said ribs an tension said covering, substantially as described.

2. An umbrella comprising a handle, ribs, a holder and a covering,—said holder being 55 slidably mounted on said handle and having a straight rod with bent-up ends depending from the holder on which said ribs are pivotally mounted, and having an outwardly flaring flange adapted to bear on the extended 60 ribs and tension said covering, substantially as described.

3. An umbrella comprising a handle, ribs, an oblong holder and a covering,—said holder being slidably mounted on said handle and provided with a depending parallel rod with

ends bent up and fastened in the holder which has fork ends an a continuous outward flange,—the ribs being loosely pivoted on said rod and those at the ends being slideable on the bent-up ends into engagement with said forks, and all the ribs adapted to engage said flange and tension said covering when the holder is slid downward, substantially as described.

4. An umbrella comprising a handle, ribs, a holder and a covering,—said ribs being pivotally mounted in the holder and consisting of multiple tubular sections having hollow flexible connections at adjacent ends, slideable filler pieces in said sections, means to slide said pieces partly into adjacent sections and stiffen said connections, and retracting springs for said pieces, substantially as described.

5. An umbrella comprising a handle, tubular ribs, a holder and a covering,—said ribs being pivotally mounted in said holder and being in multiple sections provided with flexible connections consisting of coil springs secured to adjacent ends,—and slideable fillers mounted in said sections having cords extending outside to operate the fillers into locking position, and springs to retract them, substantially as described.

6. An umbrella comprising a tubular handle consisting of multiple tubular sections, hollow flexible connections between adjacent ends of said sections, filler pieces slidably mounted in said sections, means to slide said pieces partly into adjacent sections for stiffening said connections, and springs adapted to retract said pieces, substantially as described.

7. An umbrella comprising a tubular handle in multiple sections, hollow flexible connections between adjacent ends of said sections, filler pieces slidably mounted in said sections, a cord connecting said pieces with outside and having a terminal stop ball for the hand end, and a retracting spring at the other end for said filler pieces, substantially as described.

8. An umbrella comprising a covering, a handle, an oblong holder having a hole near one end for slidably mounting the handle therein and having an outward flange, multiple ribs having their ends pivotally mounted in one vertical plane in said holder and adapted to bear against said flange and tension said covering and consisting of tubular sections, hollow flexible connections for adjacent ends, spring-controlled filler pieces slideable in said sections, operating cords for said pieces, and terminal balls for said cords forming pendants for the tip ends when the umbrella is open and closers when folded.

9. The combination with multiple tubular sections, of hollow flexible coil spring connections between, and substantially the same diameter as adjacent ends of said sections to

make flush joints, filler rods slidingly mounted in said sections, and means to slide said rods partly into adjacent sections to stiffen the joints and back again to restore flexibility.

5 In testimony whereof I have affixed my signature.

WILLIAM F. SCHOENHARD.
